UNITED STATES PATENT OFFICE

2,575,473

SCREW HOLDING SCREW DRIVER

Forbie O. Selseth, Minneapolis, Minn.

Application August 5, 1946, Serial No. 688,551

2 Claims. (Cl. 145—50)

1

This invention relates to a device for handling screws or other small articles, particularly articles having a slot therein. It often happens that a screw having a slotted head must be removed from or inserted in a location which is difficult to reach with the hand. It is desirable to have a tool which can engage the screw and hold it so that it can be inserted into a small place and engaged by its threads. It is also desirable to have such a tool which is simple and can be operated by one hand.

It is an object of this invention therefore to provide a simple and efficient implement or tool for handling screws with slotted heads and other articles.

It is another object of the invention to provide an implement for handling screws and other articles comprising a member having a portion adapted to be held in the hand, said member being in the form of a tube at one end, a pair of thin resilient plates secured adjacent said end and projecting therefrom, said plates extending across the bore in said tube and the lower ends of said plates tending to spring apart, together with a second member movable in said tube and being constructed and arranged to be moved over said plates to move their free ends together.

It is a further object of the invention to provide an implement for handling screws or other articles comprising a member having a shank, one end of which is formed as a tube, a pair of thin resilient plates secured adjacent the end of said tube, said plates extending across the bore in said tube and having projecting portions adapted to spring apart, a plunger extending through said member having a bifurcated end adapted to move over said plates and move the free ends thereof together, said plunger projecting at the other end of said member and having a knob or handle means thereon by which it can be moved over said plates, together with resilient means for moving said plunger in the opposite direction to free said plates.

These and other objects and advantages of the invention will be fully set forth in the following description made in connection with the accompanying drawings in which like reference characters refer to similar parts throughout the several views and in which—

Fig. 1 is a view in side elevation of the device;
Fig. 2 is a view similar to Fig. 1 showing the device in another position;

Fig. 3 is a central vertical section of the device, as shown in Fig. 1, and shown on an enlarged scale;

2

Fig. 4 is a partial view in central vertical section taken substantially on line 4—4 of Fig. 3;

Fig. 5 is a horizontal section taken on line 5—5 of Fig. 3;

Fig. 6 is a horizontal section taken on line 6—6 of Fig. 3;

Fig. 7 is a horizontal section taken on line 7—7 of Fig. 3, said sections being taken as indicated by the arrows; and

Fig. 8 is a partial view in side elevation showing the device holding a screw.

Referring to the drawings, a device is shown comprising a member 10. While this member could be variously formed, in the embodiment of the invention illustrated it is shown as cylindrical or as having a cylindrical shank, and one end 10a of said member, which can be called the lower end, is of reduced diameter and in the form of a tube. Portion 10a adjacent its lower end is slotted transversely and a pair of quite thin resilient plates 11 are secured against the sides of said slot in any suitable manner, as by welding or brazing, said plates 11 projecting some distance below portion 10a, and are arranged so that their free ends tend to spring apart, as shown in Figs. 1 and 3. Member 10 has a bore extending therethrough coaxial with the bore in portion 10a and a second member or plunger 12 is disposed in said bore. The lower end of plunger 12 is bifurcated or provided with a slot 12a the sides of which are parallel to the flat sides of plates 11 so that said slot can embrace plates 11. The bore in member 10 is provided with an enlarged portion 10b and a coiled compression spring 13 is disposed in portion 10b, the same encircling plunger 12 and having one end engaging one end of portion 10b. A small pin 14 extends transversely of plunger 12 and is secured therein and said pin is engaged by the other end of spring 13. Plunger 12 normally projects at the upper end of member 10 and has a handle portion 15 shown as in the form of a knob secured thereto, said knob having a rounded upper end.

When the implement is to be used to engage a screw 16, the same will be held in the hand and the operator can press on knob 15 with his thumb or forefinger. This will move plunger 12 downwardly into member 10 and cause the lower end thereof to move over plates 11 so that said plates are brought into engagement, as shown in Fig. 2. With the plates in this position they are inserted into the groove 16a in the head of screw 16 and the knob 15 is then released. Spring 13, which was compressed when plunger 12 was moved, now

moves said plunger upwardly to the position in Fig. 1, and plates 11, due to their resiliency, spring apart and engage the sides of slot 16a so that said screw is frictionally engaged by said plates and can be lifted thereby with the implement. Screw 16 can now be placed into the desired position and given some rotation to start it into its socket. Similarly a screw which is to be removed from a place difficult of access can be engaged by plates 11 and turned from its socket and gripped by plates 11 when knob 15 is released. The screw could be initially loosened with a regular screwdriver or the implement in the position shown in Fig. 2 constitutes an efficient screwdriver. Screws can thus be very easily and efficiently handled and placed in the desired position or removed therefrom by the implement. One great advantage of the structure is that the implement can be held in and operated entirely by one hand. This is a great advantage. The implement finds effective use in assembly lines and other places where mechanism is assembled or dismantled. The device is quite simple in construction, easily made and assembled, and quite rugged and durable. The same has been amply demonstrated in actual practice and found to be very successful and efficient.

It will of course be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. A device for handling screws and other articles having in combination, a member adapted to be held in the hand and having a bore extending therethrough with an open lower end, a pair of thin resilient plates secured to the lower end of said member and extending some distance beyond said end across the bore therein, the lower free ends of said plates being adapted to spring apart and being disposed in constantly diverging relation, a plunger movable in said bore having a bifurcated lower end and being movable over said

plates to move the free ends thereof together, said plunger projecting at the upper end of said member and having a handle at its upper end, said member having an enlarged portion of said bore therein, a coiled compression spring surrounding said plunger having one end engaging one end of said enlarged bore, and means secured to said plunger engaged by the other end of said spring, said spring tending to move said plunger away from said blades.

2. A device for handling screws and other articles having in combination, a member having an intermediate portion adapted to be held in the hand, said member having a tubular portion at its lower end, said lower end being open, a pair of thin resilient blades secured adjacent the end of said tubular portion, and fixed longitudinally of said portion extending across the bore thereof and extending downwardly some distance from said end, the free ends of said blades tending to spring apart to bring the blades into a constantly diverging relation, a plunger movable in said member having a slotted lower end adapted to move over said blades to move the free ends thereof together, said plunger projecting at the other end of said member and having a knob thereon adapted to be pressed by a portion of the hand to move said plunger, and resilient means for moving said plunger away from said blades, comprising a compression coiled spring in said member engaging said plunger to move the same upwardly.

FORBIE O. SELSETH.
